UNITED STATES PATENT OFFICE

129,820

DESIGN FOR A SALT BLOCK

Milton J. Gearing, St. Clair, Mich.

Application July 30, 1941, Serial No. 102,574

Term of patent 14 years

To all whom it may concern:

Be it known that I, Milton J. Gearing, a citizen of the United States, residing at St. Clair, county of St. Clair, State of Michigan, have invented a new, original, and ornamental Design for a Salt Block, of which the following is a specification, reference being had to the accompanying drawing, forming part thereof.

Figs. 1, 2, and 3 are end, side, and perspective views, respectively, of the salt block, showing my new design.

I claim:

The ornamental design for a salt block, as shown.

MILTON J. GEARING.
